Primary Examiner — T. Chase Nelson*Assistant Examiner* — Mark Cavanna(74) *Attorney, Agent, or Firm* — Offit Kurman, P.A.; Robert R. Axenfeld**CLAIM**

The ornamental design for a torso-support apparatus, as shown and described.

DESCRIPTION

FIG. 1 is a top-isometric-view of an exemplary torso-support apparatus;

FIG. 2 a bottom-isometric-view thereof;

FIG. 3 is a right-side view thereof;

FIG. 4 is head-end-side view thereof;

FIG. 5 is a foot-end-side view thereof;

FIG. 6 is top-view thereof; and,

FIG. 7 is bottom-view thereof.

The broken lines showing the apparatus, or portion thereof, is not a part of the claimed design.
